UNITED STATES PATENT OFFICE.

JOHN A. HIRSCHBERG AND JULIUS W. HARTLIEB, OF NEW YORK, N. Y.

BLUE-PRINT FRAME.

1,075,913.

Specification of Letters Patent.

Patented Oct. 14, 1913.

Application filed October 26, 1912. Serial No. 727,862.

To all whom it may concern:

Be it known that we, JOHN A. HIRSCHBERG and JULIUS W. HARTLIEB, citizens of the United States, and residents of the city 5 of New York, borough of Manhattan, in the county and State of New York, have invented a new and Improved Blue-Print Frame, of which the following is a full, clear, and exact description.

10 This invention relates to appliances for making blue prints or the like, and has particular reference to a frame or holder for the drawings or tracings to be reproduced, the same comprising a main frame adapted 15 to hold the usual glass plate and other accessories, and in connection therewith the use of clamping means in the nature of a plurality of binding strips associated with the side and end members of the main frame 20 and adapted to fold inwardly simultaneously adjacent the inner edge of the frame into co-operation with the said accessories.

The primary object of this invention is to 25 so mount said binding strips upon the main frame and operatively connect them as to make them all operable simultaneously by a single movement of an actuating member.

A further object of this invention is to 30 facilitate the manipulation of large frames of the character referred to whereby a great amount of time now commonly wasted is saved in the placing of work into or removing the same from a large frame, and the labor incident thereto is materially reduced.

35 The foregoing and other objects of this invention will be hereinafter fully described and claimed and illustrated in the drawings accompanying this specification in which like characters of reference indicate corresponding parts in all the views, and in which—

Figure 1 is a plan view of one embodiment of the invention shown as applied to a printing frame in the position it occupies when 45 being manipulated; that is to say, with the back or the side opposite the glass plate upward; Fig. 2 is a transverse sectional detail substantially on the line 2—2 of Fig. 1; and Fig. 3 is a detail of the actuator and locking 50 means.

Referring particularly to the drawings, we show at 10 a frame of any suitable size, the same being provided with an inwardly projecting flange 11 adapted to receive and 55 support the usual glass plate 12 adjacent to which the work to be reproduced and the

sensitized paper are to be secured by any suitable means including, for example, a layer of felt 13 and a flexible impervious diaphragm 14. According to the usual 60 practice, this diaphragm is made of rubber or rubber composition, and is fitted with a nipple 15 to which air exhausting means of any suitable nature may be applied for the purpose of withdrawing the air from between the same and the glass plate, whereby 65 the ordinary atmospheric pressure operating upon the outsides of the diaphragm and the glass plate will insure the intimate contact between the work and the inner face of the 70 glass plate.

In operations as heretofore carried on with mechanism of the nature already set forth, it is customary to employ an auxiliary frame for the purpose of securing the 75 margin or edge of the diaphragm into substantially air-tight contact with the edge of the glass plate directly opposite the flange 11. Such auxiliary frames, however, used in connection with large printing frames are 80 exceedingly heavy and necessitate the use of overhead hoisting tackle for the purpose of lifting and shifting them preparatory to the loading of a frame or in the subsequent removal of the work therefrom. Not only is 85 such an auxiliary frame heavy and unwieldy, but in order to provide reliable means to secure it in place for the purpose set forth, the means heretofore proposed have been very slow and otherwise unsatisfactory. We, therefore, employ a series of 90 binding strips 16 on the sides and ends of the main frame which take the place of the heretofore proposed auxiliary frame. Each of these strips is independent of all the others 95 with respect to its construction, but we employ means for supporting and operating said strips whereby they will all move simultaneously into locking position, and accordingly a single locking means may be employed to secure them in such position in any convenient manner.

As a practical embodiment of suitable means for operating the several binding strips, we provide as many rock shafts 17. 105 Each rock shaft is suitably journaled in bearings 18 in the corresponding member of the main frame, the shaft being substantially housed in place beneath a cap 19 which serves to inclose the bearings 18 as well as 110 the rock shaft. Each strip 16 is rigidly secured to the adjacent rock shaft 17 by any

suitable number of arms 20 connected by means of set screws or the like 21 to the shaft, whereby upon rotation of the rock shaft the strip connected thereto will be 5 positively moved through the arc of a circle into or out of closed position. The cap 19 is cut away as indicated at 19' for the accommodation of the arms 20 as they swing outwardly.

10 As suitable means for connecting the rock shafts for simultaneous operation, we provide between each two of them a pair of miter gears 22, said gears being rigidly connected to the shafts. One of the shafts is 15 extended, as indicated at 17', so as to project beyond the main frame, and to it is connected an actuator shown in the form of a lever 23 whereby the shaft to which it is connected may be operated in either direction and hence the corresponding operation of all of the shafts will result. A ratchet 24 is shown secured to the shaft extension 17' and is adapted to be locked by means of a spring actuated pawl 25 so as to lock the 20 binding strips 16 in contact with the diaphragm.

25 When it is desirable, each of the strips 16 may be faced on the side adjacent the diaphragm with a pad 26 of felt or other 30 suitable material, whereby a more satisfactory coöperation with the diaphragm may be had and damage to the diaphragm will be prevented.

The operation of the device may be briefly 35 set forth as follows: With the frame in the position indicated in Fig. 1, in order to open the same for the reception or removal of the work, the actuator 23 is grasped so as to permit the pawl 25 to be thrown outwardly out of engagement and the actuator is then swung through an arc of substantially 40 90 degrees, causing the rock shafts and strips 16 to swing upwardly and around the axes of the rock shafts so that they will 45 substantially occupy the position indicated in Fig. 2. In this position the binding strips will be well out of the way of the diaphragm 14 and the other accessories co-operating with the glass plate. When the 50 parts are properly placed upon the glass plate and it is desired to lock the diaphragm in place for the purpose above set forth, a reverse movement of the actuator 23 will cause all of the binding strips 16 to swing 55 into normal position where they will be locked by operation of the pawl and ratchet. It will thus appear that the operation is not 60 only a very simple one, but the locking effect is thoroughly reliable. It is to be noted also in this connection that it is a physically easy matter to manipulate this appliance on

the part of a single operator without the use of any auxiliary hoisting apparatus.

The several parts of this device may be made of any suitable materials and the relative sizes and proportions and also the number of attaching arms may be varied according to the work to be performed or the desire of the user without departing from the spirit of the invention.

Having thus described our invention, we claim as new and desire to secure by Letters Patent:—

1. The herein described blue print frame comprising, in combination with a main 75 frame and the usual printing accessories, a plurality of binding strips associated with the respective sides and ends of the frame, and means to simultaneously swing said strips through arcs of circles into or out of 80 contact with said accessories.

2. In a blue print frame, the combination with a main frame having a flange and the usual printing accessories supported upon said flange, of a series of independently 85 constructed binding strips associated with the respective side and end members of the main frame and adapted to coöperate with said accessories, a rock shaft journaled upon each frame member, means connecting each 90 binding strip to the adjacent rock shaft, and means connecting the several rock shafts for simultaneous movement, substantially as set forth.

3. In a blue print frame, the combination 95 with a main frame having side and end members and means associated therewith for supporting work, of a plurality of independently constructed binding strips associated with the respective side and end members 100 and operative normally adjacent the inner edges thereof, a rock shaft journaled within each of the main frame members, arms rigidly secured to each binding strip and also secured to the adjacent rock shaft, 105 the frame members being provided with cut-outs to accommodate said arms, means connecting all of the shafts for simultaneous operation whereby the binding strips will 110 be swung into or out of engagement with the work holding means, said shaft connecting means including beveled gears, and means to lock the binding strips in firm contact with the work.

In testimony whereof we have signed our 115 names to this specification in the presence of two subscribing witnesses.

JOHN A. HIRSCHBERG.
JULIUS W. HARTLIEB.
